DEVICE FOR TRANSPORTING BEDRIDDEN PATIENTS

George B. Nelson, Chicago, Ill.

Application August 27, 1949, Serial No. 112,693

5 Claims. (Cl. 212—14)

1

My invention relates to an invalid lifter and carrier for use in hospitals, convalescent homes, private homes, and wherever the same may be found applicable.

The invention has among its objects an efficient device for lifting and transporting bedridden patients and invalids, for example, from a bed or the like when it is desired to change or remake the bed, or to place the patient in a chair, or on a commode, or on a hospital cot, as well as to transport the patient to a different room, the patient being taken care of with a minimum of handling and discomfort, with a minimum of help. The invalid may be lifted and seated in a chair while the bed is being changed or remade, or for dressing the hair, bathing, shaving, or other operation. All of the handling may be done by the one attendant or nurse without difficulty or undue strain on the attendant, even though the invalid may be of great weight, or in a condition otherwise making handling difficult. All of this may be done in a minimum of time.

The invention has especially as an object the production of a device which enables one attendant to handle the subject more conveniently, quickly, and satisfactorily, and with more comfort than the usual manner which ordinarily may require several attendants or interns to help the nurse perform her duties.

The invention also has as an object the production of a simple, efficient, safe, and readily portable apparatus of the kind described which is not unsightly in appearance, which will operate smoothly to lift or carry the subject without danger of lifting too high or dropping, which might result in injury to the patient, the device stopping automatically when the limit of upward or downward travel is reached.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

In the drawings, wherein like reference characters indicate like or corresponding parts:

Fig. 1 is a perspective view of the device illustrating the lifting or handling of a patient, the bed and nurse being shown in dotted lines;

Fig. 2 is a side elevation of a portion of one end with the cover plate removed and some parts shown in section;

2

Fig. 3 is a sectional view through the bar connecting the spaced uprights, the shaft, and the pulley on the shaft, the same being taken substantially on the line 3—3 of Fig. 4;

5 Fig. 4 is a sectional view through the pulley taken substantially on line 4—4 of Fig. 3;

Fig. 5 is a sectional view and side elevation of the connecting and controlling means for the motor drive;

10 Fig. 6 is a sectional view of the sling or carrier;

Fig. 7 is a plan view of a modified carrier; and

Fig. 8 is a perspective view of one of the corners of the frame shown in Fig. 7.

15 Referring to the drawings, in which only one embodiment of the invention is shown, 1 and 2 represent suitable base members which are mounted on casters or rollers 3. Casters which are provided with suitable anti-friction bearings and swiveled on the base members are preferably employed. I also use casters which are rubber tired, or similarly equipped. Carried by the base members 1 and 2 and rigidly secured thereto are the uprights 4 and 5, the upper ends of which are rigidly connected by a connecting bar 6. To reduce weight the uprights 4 and 5 and bar 6 may be made of tubular material. Arranged on the upper end of the upright 4 is a bracket member 7, and a more or less similar bracket 8 is arranged at the upper end or top of the uprights 5. The brackets 7 and 8 and members 4, 5, and 6 may be provided with flanges 9 which may be detachably and rigidly secured to each other by means of the flange bolts 13. Obviously, any equivalent construction may be employed that will produce a mobile unit.

20 The brackets 7 and 8 are formed with bearing housings 10 and 11, the same containing bearings, preferably of the antifriction type, which carry a winding shaft 12, a square shaft being shown. Upon this rotatable shaft is mounted a pulley or sleeve, designated generally by the reference character 14, which may slide lengthwise of the shaft, but is prevented from rotating on the shaft 1 owing to the fact that the shaft is not round. The pulley 14 carries a winding cable 15 which in turn carries a carrier or sling, one type being shown in Fig. 1, and denoted generally by the reference character 16, having a flexible body support 17 of canvas or equivalent material, the same being described more in detail hereinafter.

25 Arranged within the housing 10 on the carrier 7 is an intermediate shaft 20 provided with bushings 21 which extend through and are carried by

the anti-friction bearings 22. The shaft 20 and winding shaft 12 are connected by a collar 23 rigidly connected thereto by the bolts or set screws 24. Secured on the shaft 20 within the housing 10 is a beveled gear 25, which may be secured to the shaft 20 by a set screw 26, or the equivalent. This gear meshes with a similar beveled gear 27 secured at the upper end of a drive shaft 28 which extends down into a tubular housing 29, square in cross-section, Fig. 1 and Fig. 5, carried by the assembly on the base 1. The shaft 28, for safety reasons, is preferably enclosed within in a non-rotatable tubular housing 30, the upper end of which is provided with a sleeve 31 carried by a bracket 32, as shown in Fig. 2. An anti-friction bearing 33 is provided at the upper end of the shaft 28, as also shown in Fig. 2.

Arranged within the housing 29 is a threaded shaft 36 which is rigidly secured to the shaft 28 by means of a collar 37. The lower end of the shaft 36 is secured to the shaft 39 extending from a reducing gear assembly 40, shafts 36 and 39 being rigidly secured together by a collar 38 and pins, as shown, similar to the collar 37 secured to the upper end of 36 and to the shaft 28. The housing 29 is supported on the base 1 through the flange 41 and bolts 42, which rigidly secure the same to the reducing gear housing, which in turn is mounted on the base 1. I have shown a reversing electric motor 43 which is suitably connected with switches in a switch box 44 mounted on the base and provided with manually operable switches 45 and 46 which control the direction of rotation of the motor and the resulting direction of motion or rotation of the shaft 28 through the reduction gear 40 and shaft 36. Extending from the switch box 44 is a conductor 47 which terminates in a manually operated two-button switch, not shown in detail, adapted to control the operation of the motor at the will of an attendant, the construction of the switch 48 being such that when either switch button is manipulated, the motor will be driven in the desired direction; but when pressure is released on the buttons, the circuit will be broken and the motor will not operate. Obviously, standard switches or circuit breakers may be used. When the shaft 28 is driven by controlling the motor it will rotate the winding shaft 12, which is driven by the shaft 28 through the gears 25 and 27.

In order to limit the driving of the winding shaft 12, I provide limit switches which are operated by means of a non-rotatable nut 50 threaded on the shaft 36, the nut 50 provided with cam faces 51 and 52 for engagement with the switch actuating mechanism buttons 53 and 54 which control switches in the switch housings 55, 56 representing electrical conductors extending to the switch box 44. The nut 50 is circular in cross-section and complementally formed to the interior of the tubular housing 29. In order to prevent rotation of the nut within the housing although permitting the nut 50 to travel vertically in either direction as the threaded shaft 36 is oppositely rotated to raise and lower the patient, a stud bolt 50', Figs. 1 and 5, extends through a vertical slot 50'', Fig. 1. The travel of the nut 50 on the threaded shaft 36 upwardly will operate the switch controlled by the button 53, while downward movement of the nut 50 will control the switch operated by button 54, which actuates the switch mechanism in that box. It will thus be seen that the rotation of the winding shaft 12 will be automatically controlled so as not to

raise the carrier 17 too high or to lower it to an undesired level.

As was before stated, the pulley 14 is adapted to travel along the rotating shaft 12 and rotate with it, the same winding up the cable 15, which has one end secured to the pulley and the other end secured to the sling or carrier device. In order to provide for the easy movement or longitudinal adjustment of the pulley 14 on the winding shaft 12, I provide suitable anti-friction means arranged within and carried by the body 58 of the pulley.

Referring to Figs. 3 and 4, the pulley body 58 is provided with lugs or spurs 60 and 61, which rotatably carry pins 62, and on these pins are arranged rollers 63 which roll on the winding shaft and make sliding of the pulley on the shaft comparatively easy. Shells or enclosures 63 enclose the rollers, the shells being secured to the lugs by means of screws 65, or their equivalents.

Carried by the cable 15 is a weight 66 which tends to hold the cable slightly taut when the carrier or sling is removed. The carrier or sling frame, indicated generally by the reference character 16, consists of the connected members 67 and 68, which are arranged to engage a hook on the end of the cable 15. At each corner of the frame 16 is an eye 69 to which the sling proper is connected by means of straps 70 and snaps 72. The sling shown consists of a canvas 74 provided with rings 73 at the corners which may be engaged by the spring snaps 72.

Referring to Figs. 1 and 6, the canvas part 74 of the sling is provided with a cut-out portion 75 which normally is closed by a flap 76 stitched at 77 at one end to the body canvas 74, and secured by snaps 78 at the opposite end. The flap 76 may be released and opened to uncover the opening 75 of the sling when it is desired to place the patient over a commode or bedpan.

The sling shown in Fig. 1 may not always be desirable for carrying the patient, depending upon the infirmity of the patient, and in some instances it may be desired to carry the patient stretched out. For this purpose I provide a sling consisting of a frame having end and side rods 80 and 81, respectively, which carry a canvas stretcher-like body 85 hemmed at the edges so that the side rods 81 may be threaded through the same. The rods 80 and 81 may be rigidly secured together by means of corner brackets 82, either one or both of which may be locked to the corner bracket by means of thumb nuts 83. Each of the corner brackets is provided with a ring 84 for engagement with snaps on straps secured to the corners of the frame 16. As with the sling 74, the canvas 85 may be provided with an opening 86 normally covered by a flap 87 secured at one end 88 to the body of the canvas and detachably secured at the other end by means of snap fasteners 89.

In using the device, referring to Fig. 1 in which a bed and attendant or nurse are shown in dotted lines, the lift is moved or positioned so that the winding shaft 12 extends across the bed. The sling 17 may be opened on the bed and the patient moved or rolled over on the canvas 74, after which the canvas may be attached to the frame 16. The attendant may now press the button suitable to drive the motor in a direction to rotate the shaft 12 and wind the cable 15 on the pulley 14, raising the patient from the bed. If the attendant releases the switch button, the motor 75 will stop and hold the sling elevated. The bed

may now be changed or the sling with the patient carried thereby may be moved to the side to facilitate making the bed, or to move the patient over a chair or commode. If it is desired to lower the patient back to the bed or on a chair, the sling will be moved on the winding shaft 12 to the desired point to center the patient on the bed or chair, after which, by pushing the proper button in 48, the motor will be driven in a direction to lower the patient. Should the attendant fail to push the proper button or release the button to stop the motor, one of the limit switches shown in Fig. 5 will be actuated to stop the motor. It will thus be seen that the patient may be handled, lifted, or lowered without any effort other than operating the switch 48. The sling carrying the patient may be moved along the winding shaft 12 without effort due to the ease in which the pulley 14 slides on shaft 12. Of course, the whole apparatus may be rolled around the room or down a corridor to another room with a minimum of physical effort on the part of a single attendant. A patient may be readily picked up off of a bed and placed on a cart to go to the operating room, or after lifted from the cart, back to the bed. Where it is desired that the patient be kept stretched out, the carrier shown in Fig. 7 may be employed, this type of carrier being desirable in certain cases.

As was previously mentioned, the device is particularly suitable for use in hospitals where there may be a shortage of attendants, since a single nurse, attendant or intern may handle the patient far better than three or four attendants, as done in the usual manner, and without any physical exertion on the part of the attendant, or discomfort or injury to the patient. It is especially desirable in convalescent homes as well as in a private home where there may be only a practical nurse to take care of a patient bedridden for periods of months or years. By enabling the attendant to lift the patient from the bed to change the bed, the danger of bed sores is minimized, and where the patient is ordinarily helpless to aid himself, he may be rested by placing him in a chair, or may be relieved on a commode without requiring the use of the never to be forgotten bedpan, which has always been a terrible punishment for an invalid.

Having thus described my invention, it is obvious that various immaterial modifications may be made in the same without departing from the spirit of my invention; hence I do not wish to be understood as limiting myself to the exact form, construction, arrangement, and combination of parts herein shown and described, or uses mentioned.

What I claim as new and desire to secure by Letters Patent is:

1. In an invalid lifter and carrier of the kind described and in combination, two bases, an upright rigidly secured to each base and a connecting bar rigidly secured to the upper ends of said uprights, a rotatable winding shaft carried by said uprights, a pulley slidably carried on said shaft but non-rotatable thereon, a drive shaft, a motor mounted on one of said bases adjacent the upright carried thereby, a reduction gear operatively connected with said drive shaft and with said motor, means for connecting said drive shaft with said rotatable winding shaft, limit switches for automatically controlling the operation of the motor, and a manually controlled switch for controlling the motor to control the direction of rotation of the drive shaft and the extent of rotation.

2. In an invalid lifter and carrier of the kind described and in combination, two bases, an upright rigidly secured to each base and a connecting bar rigidly secured to the upper ends of said uprights, a rotatable shaft carried by said uprights, a pulley provided with a plurality of rollers and slidably carried on said shaft by said rollers, but non-rotatable thereon, a reversible motor mounted on one of said bases adjacent the upright carried thereby, a drive shaft, a reduction gear operatively connected with said drive shaft and with said motor, means for connecting said drive shaft with said rotatable shaft, limit switches for automatically controlling the operation of the motor, and a manually controlled switch controlling the motor to control the direction of rotation of the drive shaft and the extent of rotation.
3. In an invalid lifter and carrier of the kind described and in combination, two mobile bases, an upright rigidly secured to each base and a connecting bar rigidly secured to the upper ends of said uprights, a winding shaft extending between and rotatably carried by said uprights at their upper ends, a pulley slidably carried on said shaft and rotatable therewith, a reversible electric motor mounted on one of said bases, a rotatable drive shaft, a reduction gear operatively connected with said drive shaft and with said motor, means for connecting said drive shaft with said rotatable winding shaft, limit switches for controlling the operation of the motor, and a manually controlled switch controlling the motor to control the direction of rotation of the winding shaft and the extent of rotation.
4. In a device of the kind described and in combination, a pair of bases each provided with casters, an upright carried by each base and rigidly secured thereto, each upright provided with a head at the upper end thereof rigidly secured to the uprights, a bar connecting said heads and rigidly secured thereto, a winding shaft extending between said heads and rotatably carried thereby, a pulley arranged on said shaft and slidably lengthwise thereon, anti-friction rollers interposed between the pulley and shaft, the pulley rotatable with the shaft, a reversible motor arranged on one base, a vertical drive shaft, a reduction gear operatively connecting the lower end of said shaft with said motor, means at the upper end of said drive shaft for driving the connection of the upright shaft and said winding shaft carried by said uprights, a manually operated switch operatively connected with said motor for controlling the starting and stopping of the same, or reversing its direction of rotation, limit switches for automatically limiting the rotation of said drive shaft in either direction, carrier means and a cable extending from said carrier means to said pulley and secured thereto.

5. In a device adapted for raising and lowering, comprising in combination, a pair of bases each provided with casters, an upright carried by each base and rigidly secured thereto, each upright provided with a head at the upper end thereof rigidly secured to the uprights, a bar connecting said heads and rigidly secured thereto, a winding shaft extending between said heads and rotatably carried thereby, a pulley slidably arranged on said shaft but non-rotatable thereon, a reversible motor arranged on one base, a vertical drive shaft, a reduction gear operatively connecting the lower end of said shaft with said motor, means at the

upper end of said drive shaft for drivingly connecting the upright shaft and said rotatable winding shaft carried by said uprights, a manually operated switch operatively connected with said motor for controlling the starting and stopping of the motor or reversing its direction of rotation, limit switches for automatically controlling the motor and limiting the rotation of said drive shaft in either direction, supporting means adapted to be raised and lowered and moved laterally in either direction on said shaft, and a cable extending from said supporting means to said pulley and secured thereto.
